UNITED STATES PATENT OFFICE.

WILLIAM B. REED, OF WESTFIELD, MASSACHUSETTS, ASSIGNOR TO THE H. B. SMITH COMPANY, OF WESTFIELD, MASSACHUSETTS, A CORPORATION OF MASSACHUSETTS.

DESIGN FOR A RADIATOR.

48,045.

Specification for Design.

Patented Oct. 26, 1915.

Application filed July 9, 1915. Serial No. 39,008. Term of patent 14 years.

To all whom it may concern:

Be it known that I, WILLIAM B. REED, a citizen of the United States, and a resident of Westfield, in the county of Hampden, State of Massachusetts, have invented a new and original and ornamental Design for a Radiator, of which the following is a specification, reference being had to the accompanying drawings, forming part thereof.

In the drawings Figure 1 is a side view of

a complete radiator. Fig. 2 is a plan view thereof.

I claim—

The ornamental design for a radiator as shown.

WILLIAM B. REED.
